ABSTRACT

Warps drawn out of a suitable number of warp bobbins are simultaneously processed to obtain consecutively a unit group of dyed warps arranged for a subsequent weaving operation in accordance with a predetermined weaving plan. Said group of warps is wound in a predetermined color arrangement on a warp winding bobbin. Any number of said color arranged warp winding bobbins are skewered on a bar to make a skewered and wound bobbin. Any number of said skewered and wound bobbins are supported on a frame to obtain the total number of warps required for subsequent weaving operation.

PROCESS FOR WRAPPING IN WEAVING AND APPARATUS THEREOF

This is a continuation-in-part application of Ser. No. 858,306, filed Sept. 16, 1969.

BACKGROUND OF THE INVENTION

An object of the present invention is to provide an apparatus and a process for bleaching, dyeing and sizing and otherwise finishing warps and arranging them in a predetermined color arrangement on bobbins for use in a subsequent weaving operation.

Another object of the present invention is to provide an apparatus and a process for mechanically collecting and supporting unit color arranged warp winding bobbins one after another. Another object of the present invention is to provide a simple and inexpensive apparatus and process for consecutively performing the most difficult warping operation in a weaving process.

In accordance with this invention, therefore, it is not necessary to manually arrange individual colored warp bobbins which have been separately dyed and otherwise finished on a creel stand. Thus, this invention saves a considerable amount of time and trained labor. In addition, unit color arranged warp winding bobbins are collected and supported mechanically on a frame. Here again, this invention saves a considerable amount of time and trained labor.

In weaving a striped fabric consisting of a repetition of a unit color arrangement, individual warp cheeses have heretofore been hank reeled, and separately bleached, dyed and otherwise liquid treated to be the required colors. After sizing, such warps in hank form have been dried in a drying apparatus for a certain period of time, and separately rewound according to color. Next, as many as several thousands of individual cheeses have been arranged in a predetermined color on a creel stand by trained laborers.

Each colored warp so obtained has been wound on a warping machine, and then on a beam. These processes have constituted warping operations suitable for weaving a cloth. Such warping operations have been regarded as difficult and time consuming operations and are the very reason why weaving multi-colored patterns is regarded as very difficult.

In accordance with this invention, however, a unit group of colored warps arranged as desired is obtained during a consecutive liquid treatment of warps without the necessity of hank reeling. And an ultimate warp is obtained by collecting and supporting a plurality of said unit groups in a predetermined arrangement. Thus, the process of this invention is quite consecutive, and the complicated and difficult creel stand system is eliminated. In addition, the operations of hanking and rewinding may be markedly simplified. Thus, operations are so simplified that the number of warp breaks is greatly reduced. Thus, it may be said that this invention has made a great improvement in the preparation of threads to be used as warps in subsequent weaving operations.

Now the present invention will be described in detail with reference to the accompanying drawings.

BRIEF DESCRIPTION OF THE DRAWINGS

FIG. 1 is a diagrammatic side elevational view of the warping system embodying the present invention;

FIG. 2 is a sectional view of a bobbin for winding a unit color arranged warp;

FIG. 3 is a perspective view of a skewed and wound bobbin;

FIG. 4 is a perspective view of a group of warp winding bobbins supported by a supporting frame;

FIGS. 5, 6 and 7 are respectively cross-sectional views of the bleaching, dyeing and sizing baths shown in FIG. 1;

FIG. 8 is an enlarged view of the bleaching bath; and

FIG. 9 is a detail view of the reel shown in FIG. 1.

DETAILED DESCRIPTION OF THE INVENTION

The numeral 1 designates ten warp cheeses which are rotatably supported in parallel. The term "warp thread" as employed herein refers to a single strand of one thread or a plurality of threads spun together in any conventional manner. The numeral 2 designates a bleaching bath. The numeral 3 designates a guide roll for the bleaching bath. The bleaching bath is designed to treat ten warp threads at a time. As shown in FIG. 5, a bleaching liquid 2' is provided in the bleaching bath 2, and the single roll 3 extends across the length of bath 2. Roll 3 is rotatably attached with its lower part immersed in bleaching liquid 2'. Thus, the surface of roll 3 always has the bleaching liquid applied thereto. Ten yarns 1' drawn from the ten cheeses 1 contact the surface of roll 3 at predetermined distances from one another and run parallel with one another. Here the bleaching liquid on the surface of roll 3 is applied to the ten yarns 1', which are thereby bleached.

The threads are drawn over roll 3 as shown in FIG. 8. The container 30 of bleaching bath 2 is shaped as shown. A dyeing roll 3 has its lower part 3' immersed in the liquid bleach filling container 30. The side 3'' of the dyeing roll 3 projects laterally further than the extreme portion 30' of the container 30. Liquid bleach is supplied through entrance 31 and exits from outlet 32. The quantity of bleach solution is thus controlled so that it is always at the same level. The threads 1 pass over guide roll 33 and are brought into contact with the side 3'' of the dyeing roll 3, and advance in a curved direction without being touched by the extreme portion 30' of the container 30 before they are led to a guide roll 34. The threads are bleached when brought into contact with the side 3'' of the dyeing roll 3 which is rotating in the direction of the arrow.

The dyeing and sizing baths have the same structure as the above described bleaching bath, and accordingly will not be described in further detail.

The numeral 4 designates a dyeing bath and the numeral 5 designates a dyeing roll, ten of which are provided side by side such that each respective bleached warp thread may be dyed with a predetermined different color. As shown in FIG. 6, the dyeing bath 4 consists of ten baths separated from one another by means of partitions 4', each of which is placed between any two baths. Thus, there is no mixing of the dyeing liquid among the ten baths. Each dyeing liquid 5' in the ten baths may be different from the other nine. Each separate dyeing bath is provided with a rotatable dyeing roll 5. Thus, there are ten such dyeing rolls in all. Each such dyeing roll 5 always has the lower part thereof immersed in its respective dyeing liquid 5'. As each roll 5 rotates, its entire surface always has its respective dyeing liquid applied thereto. Thus, each of the ten yarns bleached in the bleaching bath 2 contacts the surface of one of the ten dyeing rolls, whereby the

ten yarns are acted upon by the dyeing liquids 5' on the surfaces of ten dyeing rolls, and each of the yarns is dyed a different color.

The numeral 6 designates a sizing bath and the numeral 7 designates a sizing roll, 10 of which are provided side by side such that the color of each respective colored warp thread will not be blended. As shown in FIG. 7, the sizing bath 6 consists of ten baths separated from one another by means of partitions 6', each of which is placed between any two baths. Thus, there is no mixing of sizing liquid among the ten baths. A sizing liquid 7' is contained in each separated sizing bath which are provided with individual rotatable sizing rolls 7, the lower parts of which are always immersed in the sizing liquid 7'. As each roll 7 rotates its entire surface thereof always has the sizing liquid 7' applied thereto.

Thus, the yarns dyed different colors in the dyeing bath move forward while contacting the surfaces of the 10 sizing rolls 7 and thereby absorb the sizing liquid 7' from the surfaces of the sizing rolls. It is not necessary, of course, that there should be ten kinds of sizing liquids. One kind of sizing liquid is satisfactory. But the colors of yarns immediately after dyeing may run somewhat into the sizing liquid. If this phenomenon continues, the sizing liquid in the bath may be colored with respective different colors. Thus, the sizing bath 6 is divided into 10 separate baths to prevent colored sizing liquid from mixing. In the event that the bleaching liquid is acidic and the dyeing liquids are alkaline, or vice versa, it will be necessary to provide a conventional drying device between bleaching bath 2 and dyeing bath 4. However, if the bleaching liquid and dyeing liquids are both acidic or both alkaline, then it is unnecessary to provide such a drying device.

Furthermore, since there are 10 separate sizing baths, there is no need to dry the dyed threads before they enter the separate sizing baths.

The numeral 8 designates a drying chamber provided with a timing reel device 9 which moves the 10 treated warp threads side by side and consecutively dries them. The 10 colored yarns bleached, dyed and sized in the preceding processes are arranged in a rank and are adjusted by means of a guide 11. Then they run parallel and spaced from one another into the timing reel device 9. In FIG. 9, 101 designates a driving shaft, 102 a ratchet wheel for rotating a main shaft 103, 104 an endless chain, and 105 a ratchet wheel for the main shaft. The endless chain 104 moves the main shaft in response to rotation of driving shaft 101. 106 designates a frame for the reel 9 fixedly provided near the ends of the main shaft 103. 107 is a ratchet wheel provided on driving shaft 101 for rotating an endless chain 108. 109 designates a ratchet wheel movably fixed to main shaft 103, and endless chain 108 moves ratchet wheel 109 in response to rotation of driving shaft 101. 110 and 111 are screw gears which are positioned to mesh in a correlated manner by changing their direction of rotation 90°. A plurality of pairs of screw gears 110 and 111 are positioned radially on frame 106 with main shaft 103 as the center. A plurality of ratchet wheels 112 are provided on the shafts supporting screw gears 111. A plurality of ratchet wheels 113 are positioned radially outwardly on frame 106 from wheels 112. The number of ratchet wheels 112 is the same as that of the ratchet wheels 113, and a plurality of endless chains 114 move

the ratchet wheels 112 and 113 in a correlated manner. A plurality of ratchet wheels 115 are provided on the same shafts supporting ratchet wheels 113. A plurality of ratchet wheels 116 are longitudinally aligned with ratchet wheels 115 near the outer circumference of the lower part of the frame 106. The number of ratchet wheels 116 is the same as that of the ratchet wheels 115. A plurality of endless chains 117 move the ratchet wheels 115 and 116 in a correlated manner. All of the endless chains 117 are located in such a way as to form the outer cylindrical surface of the reel 9. By the rotation of the main shaft of the reel, the yarns are wrapped on the circumferential surface of reel 9. But what constitutes this surface of the reel is not a static surface, but a number of chains always moving from the top to the bottom. Thus, each of the yarns which enter the reel moves towards the lower portion thereof while being revolved round the reel. When the yarns approach the bottom of the reel, they advance to a traverse yarn guide 11 which is provided with 10 grooves therein (see FIG. 2). Said traverse yarn guide 11 leads the yarns to a winding bobbin 13 as shown in FIG. 2. By the rotation of the drive roller 14 which is in contact with the outer circumference of the wound yarns 15 on the winding bobbin 13, the 10 yarns of different colors are wound on bobbin 13 in an arranged order. The numeral 10 designates a circulating device for circulating drying air so that the yarns are dried as they traverse reel 9.

The bobbin 13 has a longitudinally extending opening therethrough. A bar 16 has a diameter to fit within this opening and a length to extend through a desired number, such as 10, bobbins 13. Thus, 10 bobbins 13, each of which has wound thereon 10 yarns of different colors, are respectively skewered on bar 16 by hand according to a prearranged order in such a way as to be freely movable. Such an arrangement provides a situation in which 10 sets of 10 yarns of different colors, that is 100 yarns, are arranged in a predetermined manner to form a skewered and wound bobbin 17.

A suitable or desirable number of skewered and wound bobbins 17 are arranged on a cylindrical frame 18. Frame 18 may be any suitable device arranged to support the ends of bars 16 of the skewered and wound bobbins 18. In FIG. 4 there are shown eighteen bobbins 17 arranged around the periphery of frame 18. It is to be understood that frame 18 may be adapted to contain any number of bobbins 18. A particularly useful arrangement would include fifty skewered and wound bobbins 17, thus providing 5,000 treated yarns to be used in subsequent weaving operations. Thus, the arrangement shown in FIG. 4 provides a great quantity of yarns 19 of various colors in a predetermined arrangement for use in a subsequent weaving operation.

The apparatus and process for warping in accordance with this invention eliminates the use for skilled labor required for a creel stand, eliminates a substantial part of heretofore frequent winding and similar operations, and reduces the number of yarn breaks.

What is claimed is:

1. A process for preparing colored, wound warp yarns for use in a weaving operation, said process comprising the steps of withdrawing a plurality of untreated warps from a plurality of warp bobbins; passing said

plurality of warps through a bleaching bath, thereby bleaching said warps; simultaneously passing each of said plurality of bleached warps through a separate dyeing bath, each of said dyeing baths having different color dye therein, thereby dyeing each of said warps a different color; simultaneously passing each of said plurality of dyed warps through a separate sizing bath, thereby sizing each of said warps; passing said plurality of warps in predetermined spaced and parallel alignment through a timed reel drying device, thereby drying said warps; passing said plurality of warps from said time reel drying device onto a winding bobbin, thereby winding said plurality of different colored warps on said winding bobbin in a predetermined spaced relationship; arranging a predetermined number of said thus wound winding bobbins on a bar thereby forming a skewered and wound bobbin; and arranging a predetermined quantity of said skewered and wound bobbins around the periphery of a frame device; thus providing for use in said weaving operation a group of said colored, wound warp yarns arranged in predetermined pattern and of a number equal to said plurality times said number times said quantity.

2. In a system for preparing colored, wound warp yarns for use in a weaving operation and of the type including means for bleaching, dyeing sizing and drying

the warp yarns and a rewind device for rewinding the thus treated warp yarns, the improvement comprising the arrangement wherein said bleaching means is a bleaching bath through which a plurality of warps are adapted to be drawn, whereby said warps are bleached; said dyeing means comprises a plurality of separate dyeing baths, each containing a different color dye, positioned such that each of said bleached warps is adapted to be drawn through one of said separate dyeing baths, whereby each of said warps is dyed a different color; said sizing means comprises a plurality of separate sizing baths positioned such that each of said dyed warps is adapted to be drawn through one of said separate sizing baths; said drying means comprises a timed reel drying means positioned for simultaneously drying said warps and passing said warps onto a winding bobbin; said rewind device comprises means for winding said plurality of warps on said winding bobbin in a predetermined and parallel alignment; and further comprising bar means to longitudinally mount a predetermined number of said thus wound winding bobbins, thus forming a skewered and wound bobbin; and cylindrical frame means for mounting on the periphery thereof a predetermined quantity of said skewered and wound bobbins.
